Primary Examiner—James Gandy*Assistant Examiner*—Cathron B. Matta*Attorney, Agent, or Firm*—James V. Lapacek**[57] CLAIM**

The ornamental design for an electrical fuse limiter for power systems, as shown and described.

DESCRIPTION

FIG. 1 is a perspective view of an electrical fuse limiter for power systems showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a bottom plan view thereof; and,

FIG. 7 is a top plan view thereof.
